UNITED STATES PATENT OFFICE.

STEVEN F. MINTON AND ROBERT E. McCLELLEN, OF GIDDINGS, TEXAS.

CAR-DOOR.

1,251,405.

Specification of Letters Patent. Patented Dec. 25, 1917.

Application filed March 27, 1915. Serial No. 17,477.

To all whom it may concern:

Be it known that we, STEVEN F. MINTON and ROBERT E. McCLELLEN, citizens of the United States, residing at Giddings, in the county of Lee and State of Texas, have invented certain new and useful Improvements in Car-Doors; and we do hereby declare the following to be a full, clear, and exact description of the invention, such as will enable others skilled in the art to which it appertains to make and use the same.

This invention relates to car doors and more particularly to a sliding door especially designed for use on box cars.

15 The invention has for its object to provide a car door of improved and simplified construction, embodying means for forming an efficient rain-proof closure when the door is moved to closed position.

20 Another object is to provide novel and efficient means for slidably supporting the door.

Another object is to provide a locking bolt adapted to lock the door in various 25 positions.

With these and other objects in view, the invention consists in the novel construction, arrangement and formation of parts as will be hereinafter specifically described, claimed 30 and illustrated in the accompanying drawings, in which:

Figure 1 represents a fragmental side elevation of a car, showing the improved door,

Fig. 2 represents a fragmental side elevation of the door, partly in section,

Fig. 3 represents a fragmental detail sectional view on the line 3—3 of Fig. 1,

Fig. 4 represents a fragmental detail sectional view on the line 4—4 of Fig. 1,

40 Fig. 5 represents a horizontal sectional view through the door and a portion of the car, illustrating the locking bolt in detail,

Fig. 6 represents a detail view, similar to Fig. 5, illustrating the door partially 45 open,

Fig. 7 represents a top plan view, partly broken away, of the lower supporting rails or tracks for the door,

Fig. 8 represents a fragmental sectional 50 view through the door, illustrating the supporting wheel therefor, and

Fig. 9 represents a transverse sectional view on the line 9—9 of Fig. 6.

Referring to the drawing in detail, where- 55 in similar reference numerals designate corresponding parts throughout the several

views, the numeral 10 indicates the body of a car including a door frame 11. Combined sealing and guiding strips 12 are suitably secured above and at one side of the door frame 11 and are formed with offset longitudinal edges 13 receiving the strips 14 of the slidable door 15. It will be understood that the vertical strip 14 of the door 15 is adapted to engage beneath the offset longitudinal edge 13 of the vertical strip 12 when the door is moved to closed position, while the upper horizontal strip 14 of the door is slidable longitudinally within the offset lower longitudinal edge of the upper horizontal guide and sealing strip 12.

A plurality of circumferentially grooved rollers or wheels 16 are rotatably mounted in the lower portion of the door 15 and project a distance below the lower longitudinal edge of the latter. A rail track 17 is secured to the lower horizontal member of the door frame 11 in spaced relation thereto, and the upper longitudinal edge thereof is rounded to fit within the peripheral groove 80 of the wheels 16 movably supporting the door 15. A guard rail 18 is secured parallel and in spaced relation to the supporting track rail 17 and is partially inclosed by and slidably received within the angular lower 85 extremities of straps 19 secured to the lower portion of the door 15. The guard rail 18 is of considerably greater width than the track rail 17 providing a guard for the latter and engages the outer surface of the door 90 15 for preventing outward swinging movement of the latter. The rails 17 and 18 are supported by bolts 17^a, which are anchored in the door frame 11, and spacing members 18^a are positioned upon the bolts 17^a 95 between the track rail and guard rail to maintain the parts in properly spaced relation.

A vertically disposed L-shaped strip 20 100 is secured to the vertical member of the door frame 11 opposite that which carries the strip 12 and is adapted to coöperate with the vertically disposed strip 21 secured to the inner surface of the door 15.

A spring plate 22 is secured in horizontal position to the door 15 and the free end thereof is looped, as at 23, to provide an adequate handle whereby the end thereof may be swung outwardly from the door. A 115 U-shaped strap 24 is secured to the door and incloses the spring plate 22 for limiting the

outward movement thereof. Adjacent its free end a locking bolt 25 is secured to the spring plate 22, extends inwardly through a suitable aperture formed in the door 15 and is adapted to engage within any one of a plurality of notches or recesses 26 formed in a horizontally disposed rail 27 secured to the car body 10. The notches or recesses 26 are so arranged as to receive the bolts 25 and lock the door 15 when the latter is moved to either open or closed position, and also in several intermediate positions, and it will be understood that the tension of the spring 22 normally retains the bolt 25 in engagement with the outer surface of the horizontal rail 27 or one of the notches 26.

What we claim is:—

1. In combination, a door frame, a relatively thin track rail supported in spaced parallel relation to the lower horizontal member of said door frame, a guard rail of considerably greater width than the track rail, projecting above and below and supported in spaced parallel relation to the latter, a slideable door extending downwardly between the lower horizontal member of the door frame and said guard rail, rollers carried by said door adapted to travel upon the track rail, means for guiding the upper end of said door, and means for retaining

said door in frictional engagement with the inner surface of the guard rail to provide a seal.

2. In combination, a door frame, a relatively thin track rail arranged in parallel relation to the lower horizontal member of the door frame, a guard rail of considerably greater width than the track rail projecting above and below the latter, supporting bolts extending through the rails and anchored in the door frame, spacing members positioned upon the bolts and arranged between the door frame and track rail, and between the track rail and guard rail to maintain the parts in spaced parallel relation, a slideable door extending downwardly between the lower horizontal member of the door frame and guard rail, and grooved rollers carried by said door adapted to travel upon the track rail, means for guiding the upper end of the door, and means for retaining said door in position between the guard rail and door frame.

In testimony whereof we affix our signatures in presence of two witnesses.

STEVEN F. MINTON.

ROBERT E. McCLELLEN.
